UNITED STATES PATENT OFFICE.

ARTHUR HAMMER, OF BERLIN, AND FRITZ EGERSDÖRFER, OF CHARLOTTENBURG,
GERMANY.

IRONING-MACHINE.

1,220,510.

Specification of Letters Patent.

Patented Mar. 27, 1917.

Application filed July 14, 1914. Serial No. 850,898.

To all whom it may concern:

Be it known that we, ARTHUR HAMMER and FRITZ EGERSDÖRFER, both subjects of the German Emperor, residing at Berlin and 5 Charlottenburg, Germany, respectively, have invented certain new and useful Improvements in Ironing-Machines; and we do hereby declare the following to be a full, clear, and exact description of the invention, such 10 as will enable others skilled in the art to which it appertains to make and use the same, reference being had to the accompanying drawings, and to letters or figures of reference marked thereon, which form a part of 15 this specification.

The object of this invention is to provide an ironing machine, in which the relative motion between the iron and the ironing-table in the ironing plane for the actual ironing, as well as the motion in a transverse direction to the first motion, which allows of 20 obtaining the necessary ironing pressure and facilitates also the introduction and the withdrawal of the articles to be ironed, are 25 both effected by power driven means.

A further object of the invention is to provide means for imparting to the iron the ironing movement as well as the movement in a transverse direction to same. In this manner 30 a considerable simplification of the driving gear of the machine is obtained, inasmuch as the drive requires to actuate only one part, viz. the iron, while the other part can remain entirely at rest. The operation 35 of the machine is also substantially facilitated by the new construction.

Further improvements relate to the driving means of the iron and to the manner of coupling this driving means with the main 40 shaft of the machine.

The drawings show the invention in several forms of construction, as follows:

Figure 1 shows the new ironing machine 45 in vertical section; Fig. 2 shows it in vertical section on the line 2—2 of Fig. 1;

Fig. 3 shows a portion of the machine in vertical section on line 3—3 of Fig. 1 to a larger scale;

Fig. 4 shows the arrangement of the 50 pedals for the couplings in plan as seen from above;

Fig. 5 also shows in plan another method of driving the iron with automatic operation of the couplings;

Fig. 6 shows this arrangement in a section corresponding to Fig. 1;

Figs. 7, 8 and 9 show details of this arrangement.

Fig. 10 is a detail side elevation showing 60 a modified form of iron guiding arrangement used herewith.

Fig. 11 is a detail side elevation showing 65 a second modification of the iron guiding device.

Fig. 12 is a detail side elevation of an arrangement wherein the iron is stationary and the table is reciprocated horizontally and vertically.

Fig. 13 is a detail side elevation of an arrangement wherein the iron is arranged for 70 vertical reciprocation and the table for horizontal reciprocation.

Figs. 10 to 13 show further modifications 75 hereinafter referred to.

As can be seen from Figs. 1—2, the frame of the ironing machine consists substantially of two parts, viz., a lower pedestal frame 1 which carries the ironing table 2 as well as the bearings for the pedals, and the upper 80 frame-like portion 3, which comprises the iron 4 and its supporting means as well as the gearing which imparts the various motions to the iron. The table 2 which consists of a hollow casting stiffened by means of 85 ribs, is supported on the end of the frame 1 by means of two bolts 5, 5, which each pass through two eyes provided on the machine frame and a corresponding transverse bore of the ironing table.

The iron 4 consists likewise of a hollow casting reinforced by means of ribs, to which the heating steam is led through two pipes 6, 6, whose lower ends can slide in swingably mounted stuffing boxes 7, 7. 90 This arrangement is omitted in Fig. 2, for the sake of clearness. The iron is supported by means of four arms 8 arranged in pairs, in which sliding rollers 9 are mounted, in a guide piece 10 extending substantially 95 over the entire length of the ironing table in such a manner, that it can be easily moved backward and forward horizontally 100 in the longitudinal direction of the table.

The guide piece 10 consists of a casting which is stiffened by means of longitudinal and transverse ribs, and which is provided with a lateral slot 11 extending over almost its whole length, in which the rollers 9, which serve for supporting the iron, run. For protection against any lubricating oil which may drip off, oil channels 12 (Fig. 2) are provided below the slot 11 in the longitudinal direction of the guide-piece 10.

The guide-piece 10 is itself mounted in such a manner, that it can be moved only in a vertical direction. For this purpose there are provided two guide members 13 which are fixed in supports 14 arranged on the upper face of the guide-piece 10 and which slide in the bores of corresponding sleeves 16 extending downward from the top 15 of the frame portion 3. The upward and downward movement of the guide-piece 10 carrying the iron 4 is imparted to it by means of four toggle levers 17, 18, the upper arms 17 of which are supported by bolts 19 mounted in the top 15 of the frame portion 3. These bolts are formed as cylinders, which are passed through corresponding bores in the top 15 which is strengthened at these places, said bolts 19 resting on the top 15 by means of a flange 20. The upper ends of the cylindrical bolts are surrounded by caps 21, against the top of which powerful helical springs 22 bear, the lower ends of said springs bearing against the flanges 20 of the supporting bolts 19. In this manner resilient stops are formed, which are able to yield under strong upward pressure of the iron.

The raising and lowering of the guide piece 10 carrying the iron is effected by the forcing sidewise or the straightening out of the toggle-levers 17, 18. This is carried out from the main driving shaft 23 mounted on the right hand side of the machine through the intermediary of two cam-disks 24 and 25 mounted on said shaft, on which run the rollers 26 and 27 of two levers 29 and 30 respectively mounted on a common bush 28. The bush 28 is rotatably mounted on the shaft 31, which rests in bearings 32, on the frame portion 3 (Fig. 3) and 33 of the frame portion 3 (Fig. 3) and which carries the driving pulley 34 on the back of the machine. The free end of the lever 30 is connected with the middle joint of the toggle-lever 17, 18 which is arranged farthest to the right by means of two short links 35, the remaining toggle-levers being connected to said right-hand toggle-lever by means of two rods 36 engaging with each of the middle joints of the toggle levers. The cams 24 and 25 are displaced with regard to one another in such a manner and are so formed circumferentially that the toggle levers are forced sidewise during substantially one half of the revolution of the shaft 23, while during the other

half of the revolution they assume the straightened out position shown in Fig. 1, which corresponds to the lowest position of the iron 4.

The reciprocating motion of the iron is likewise effected by means of an eccentric 37 which is also mounted on the shaft 23, the rod 38 of said eccentric engaging an arm 43 jointedly connected to the top 15 of the frame portion 3, the free end of said arm 75 being connected to the iron 4 by means of a link 40. The arm 43 is rigidly mounted on a shaft 41, which rests in bearings 42, 42 of the frame portion 3 and which carries at the other end an arm 39 (Fig. 2) which corresponds exactly to the arm 43, said arm 39 being likewise connected to the iron by means of a link 40.

The eccentric 37 as well as the hub 28 of the cams 24, 25 are rotatably mounted on the shaft 23, which is driven from the shaft 31 carrying the belt-pulley 34 through the intermediary of the gear wheels 45 and 46. The rigid connection of the eccentric and of the cams with the shaft 23 is effected by means of couplings 47, 48 which are actuated by pedals mounted in the lower part of the machine frame, said couplings being movable in an axial direction on the shaft 23, but not rotatable on same. The coupling 95 muffs 47 and 48 are provided each with a bolt 49 and 50 respectively on the side facing the eccentric 37 and the same disk 24, said bolts 49 and 50 being able to engage in corresponding holes 51 and 52 respectively of the portions to be coupled, when the coupling muffs are shifted from the position shown in Fig. 3 toward the right. This shifting is carried out by means of shifting levers 55 and 56 swingably mounted on the pins 53 and 54, said shifting levers 55 and 56 engaging in known manner in circumferential grooves 57 and 58 of the coupling muffs. On the pins 53 and 54 there are further mounted levers 59 and 60, 110 which are connected by means of rods 61 and 62 with the pedals 64 and 63 mounted in the lower part of the machine frame (Figs. 2 and 4). These pedals are supported on the rod 65. Besides these pedals 115 are provided three further pedals 67, 68 and 69, of which the last can also swing about the rod 65, and the former on the rod 66. The lever of the pedal 64 is, as can be seen from Fig. 4, extended at the back 120 beyond its fulcrum and is here subjected to the influence of a laterally extended carrier 70 of the pedal lever 67, in such a manner that when this pedal is lowered the back extension of the pedal 64 and accordingly the 125 rod 61 are also lowered. The carrier 70 extends over the back part of the lever 63 and causes also this to be lowered as well as causing the rod 62 to be correspondingly raised when the pedal 67 is pressed down- 130

wardly. A similar connection exists between the pedals 68 and 63; in this case however the lateral carrier 71 engages only with the backward extension of the lever 63. Finally there is also provided a carrier 72 on the lever 69, which extends laterally over the forward arms of the pedals 63 and 64 and carries these downwardly with it, when the lever 69 is lowered.

10 A spring 71' (Fig. 1) attached at one end to the machine frame acts with its other end on the rod 61 of the lever 64 in such a manner, that the forward arm of the lever 64, as soon as it is set free from the foot of 15 the operator of the machine, again assumes its raised position automatically, while the remaining pedals stay in the lower position when they are pressed down. The raising 20 of the pedal lever 64 again by the spring 71' must however only take place when the neighboring lever 69 is in its raised position. For this purpose the strength of the spring 71' is chosen such that it can raise 25 the lever 64 when the latter is not weighed down by the lateral carrier 72 of the lever 69, but that, on the other hand, its strength does not suffice to raise also the lever 69 when the carrier 72 is resting on the lever 64.

30 The method of working the machine is as follows:

The ironing board on which is laid the article to be ironed is placed on the table 2 in the ordinary manner, so that, if a shirt is being ironed the neck band of the shirt 35 lies opposite a corresponding semi-circular recess 128 of the iron 4, so that when the iron is lowered the edge of the semicircular recess lies immediately adjacent to the neck-band of the shirt. The lowering of the iron 40 is brought about by engaging the coupling 47. For this purpose the operator steps on the pedal 64. This causes the coupling muff 47 (Fig. 3) to be shifted to the right and the cam disks 24 and 25 to be coupled with 45 the shaft 23. The roller 27 runs on the cam 25, thereby causing the toggle lever 17, 18 to be straightened out. This position is shown in Fig. 1. As soon as the iron has 50 in this manner been lowered upon the article to be ironed, the operator can release the pedal 64, if the ironing is not to be proceeded with immediately, in order to retain the iron in this position, for example when 55 it is required to exercise a continuous pressure on the article to be ironed. When the pedal is released it is brought into its upper position by the spring 71' and the coupling 47 is thus automatically disengaged, which 60 results in the stopping of the cam disks 24, 25.

According as to whether the ironing is to be carried out in the usual manner by the moving backward and forward of the iron under continual pressure on the article, or 65 whether the ironing is to be carried out in

such a manner that the iron exerts a pressure on the article only during the forward motion, but is raised during the backward motion, the operator engages only the coupling 48 or else he engages this coupling and 70 also the coupling 47. In the first case only the eccentric 37 is brought into action, causing the backward and forward movement of the iron 4, while in the latter case the cams 24 and 25 revolve simultaneously, whereby 75 the iron is constantly raised and lowered at the ends of its forward and backward strokes in such a manner that the iron is for example lowered at the right hand end of its stroke, remains lowered during the return stroke until it reaches the other end, and is then raised and kept raised during the stroke until it again arrives at the right hand end of its travel and is there lowered on to the article to be ironed. Under certain 80 conditions the arrangements could be so made, that the iron is for a short time raised at each end after completing its stroke and then again set down whereupon the movement in the other direction takes 85 place. This manner of working can be obtained by means of a simple alteration in the design and arrangement of the cams carried by the driving shaft 23. Also in the case of existing machines a corresponding method 90 of working can be subsequently obtained by exchanging the cam disks.

If it is desired to iron in the ordinary manner, *i. e.* without lifting the iron at the ends of its stroke, the coupling for the cams 100 is in the first place engaged by operation of the pedal 64, but the pedal is immediately released as soon as the iron has attained its lowest position. The spring 71' acting on the back end of the pedal 64 then causes an 105 immediate disengagement of the coupling, as already mentioned, so that the iron remains in its lower position. The pedal 63 is now depressed, whereby a continuous backward and forward movement of the 110 iron is brought about. The stopping of the iron is effected by operating the pedal 68, while the raising of the iron for the purpose of exchanging the article to be ironed is effected by a repeated short operation of 115 the pedal 64.

If it is required to iron shirts in the above described manner, then the pedal 69 is depressed, whereby the pedals 63 and 64 are simultaneously operated, which causes the 120 simultaneous engagement of the couplings for the cams as well as for the eccentric, so that the above mentioned combined movement of the iron is obtained. The setting to rest is effected by operating the pedal 67, 125 which acts simultaneously by means of its carrier 70 on the back ends of the pedals 63 and 64 and thus on the couplings 47 and 48.

If it is required to exert a pressure con- 130

stantly without the backward and forward movement of the iron, then the pedal 64 is depressed and again released as soon as the iron has reached its lowest position. If it is desired that the pressure should be repeated periodically, then the pedal 64 is held in its depressed position, so that the coupling for the cam disks 24 and 25 remains constantly engaged and the toggle-lever mechanism of the guide piece 10 carrying the iron is constantly actuated, so that the iron is moved upwardly and downwardly uninterruptedly.

In Figs. 5 to 9 another form of construction of the driving and coupling mechanism of the ironing machine is shown, which renders possible a completely automatic working of the machine, in such a manner that the operator so adjusts the machine by actuating a coupling that the machine carries out a certain number of ironing movements and thereupon automatically disengages itself. This arrangement renders it possible for an operator to serve comfortably two or more machines, since the operator does not require to bring about the stopping of the ironing operation, but can leave the machine to itself and adjust a second or third machine. In the meantime the first machine has automatically stopped its ironing, so that the operator requires only to exchange the article to be ironed and to set the machine in motion again by operating a coupling.

In Figs. 5 to 9, the main driving shaft is again denoted by the reference number 23. The said shaft also carries an eccentric 37 as well as two cam disks mounted on one hub, with which as in the case of the above described form of construction two levers 29 and 30 provided with rollers co-act, said levers being connected with the joints of the toggle-levers carrying the guiding member of the iron. On the shaft 23 there are further provided, as in the other form of construction, coupling bushes 47 and 48, by means of which the rigid connection of the cam disks and of the eccentric with the driving shaft can be effected. In this form of construction however, the engagement of the coupling is not brought about immediately by the operator, but automatically by means of controlling shafts 75 and 76, which are mounted in the machine frame beside the shaft 23. The bearings of the shafts are indicated in Fig. 5 at the ends of the shafts, but in Fig. 6 they are omitted for the sake of clearness. The construction of both controlling shafts is substantially identical, so that it will suffice to describe only one here.

On the controlling shaft 75 there is mounted an arm 77, which engages with the nose 78 of the coupling bolt 79 (Figs. 7 and 8), which is mounted movable in an axial direction in the coupling member 47 and

which can engage in a hole 51 of the hub of the cam disks 24 and 25. The coupling member 47 is mounted rigidly on the shaft 23 and cannot be shifted in axial direction on the shaft. The nose 78 of the bolt 79 is provided with an inclined surface on its side away from the coupling member 47, in such a manner, that when the arm 77 assumes the position shown in Fig. 7, the coupling bolt 79 is drawn out of the coupling member 47 against the action of its spring 80 when it runs on to the head of the arm 77, whereby the connection of the member 47 with the hub 28 of the cams 24 and 25 which is loosely mounted on the shaft 23, is removed. If therefore the arm 77 and the corresponding arm 91 of the second controlling device assume the position shown in Fig. 7, then the backward and forward and also the upward and downward movement of the iron are stopped. The duration of the pause is according to the circumferential extent of the head of the arm 77 and also to the speed of the latter. This speed also determines the number of revolutions which the cam disks 24 and 25 and also the eccentric 27 make between two pauses. The hubs common to the arms 77 and 91 and to the stepped gear wheels are pressed by coil springs 113, 113 against the left hand bearings of the controlling shafts in order to obtain a braking effect sufficient to hold the arms 77 and 91 in position against stresses exerted upon them by the bolts 79 and 79' if the spur wheels 96 and 96' are out of engagement with their step wheels.

In order to be able to alter this number, the controlling shafts 75 and 76 are provided with stepped gear wheels 93, 94 and 95, and 93', 94' and 95' respectively, the number of which can of course be increased as desired. With these gear wheels a spur wheel 96 and 96' respectively can be brought into engagement, said spur wheels being rotatably mounted on levers 97 and 97' and being in constant engagement with spur wheels 98 and 98'. The spur wheels 98 and 98' are rigidly mounted on hubs 99 and 99' respectively, which are mounted axially shiftable but non-rotatably on a shaft 100, which is driven from the shaft 104 carrying the driving pulley 103 through the intermediary of gear wheels 101 and 102. On the shaft 104 there is mounted a second gear wheel 105 which engages with the gear wheel 106 of the shaft 23.

The lever 97', which serves as controlling lever, has its end facing shaft 100 formed as a fork, the prongs 114 of which embrace the hub 99' of the gear wheel 98' in such a manner, that this gear wheel can rotate freely in the fork and the lever 97' may be swung freely about the hub 99'. The gear 98' is also adapted to be carried along when the lever 97' is shifted axially. The free end 130

of the lever 97' is provided with an extension 107, which can bear against each of the steps of a bent stepped casting 108. The steps form rests for the lever 97' and correspond to the various working positions of this lever, in such a manner that when the extension 107 bears against the steps the gear wheel 96' meshes correctly with one of the gear wheels 93', 94', or 95'.

- 10 The gear wheel 98 shown on the left hand side of Fig. 5 is arranged in the same manner as the gear wheel 98' just described. It is not like the latter however, provided with a controlling lever, but with a simple fork shaped arm 97 (Fig. 9), which serves solely for mounting the gear wheel 96 which meshes with the gear wheel 98. The hub portion of the arm 97 is rigidly connected by means of a bridge piece 112 with a ring 109 mounted loosely on the shaft 100 near the gear wheel 98'. This ring possesses a recess in which a pawl 110 mounted on the control lever 97' can engage. The pawl 110 is forced against the ring 109 by means of a spring 111, so that when the recess in this ring lies opposite the end of the pawl, the latter snaps in, so that the ring together with the arm 97 connected with it by means of the bridge piece 112 becomes rigidly connected with the controlling lever 97'. This is the case, when the positions of the levers 97 and 97' with regard to the stepped wheels 93, 94 and 95 and 93', 94', and 95' correspond to one another. The pawl 110 can be released by a pressure on the long arm of the pawl and the rigid connection of the arm 97 with the lever 97' thereby can be removed.

The object of the device is to render possible the putting into operation of one of the stepped wheels 93', 94', 95' either by itself or together with one of the stepped wheels 93, 94 and 95, according as to whether one requires only a backward and forward movement of the iron 4 by means of the eccentric 37 or whether one desires to have simultaneously an upward and downward movement of the iron by means of the cam disks 24 and 25. By bringing the gear wheels 96, 96' into engagement with larger or smaller wheels of the stepped wheels, the shafts 75 and 76 rotate at a smaller or higher rate of speed, and accordingly the bolts 79 and 79' of the couplings for the cams and the eccentric are automatically disengaged after a greater or smaller number of revolutions of the shaft 23 and after a correspondingly greater or lesser number of backward and forward and of upward and downward movements of the iron. The required synchronism of the backward and forward movements and also of the upward and downward movements of the iron is assured by deriving both movements from the common driving shaft 23, while the simultaneous disengagement of the gearings which

bring about the two motions is assured by the fact that the controlling shafts 75 and 76 revolve always at the same speed, which in its turn is attained by the fact that the gear wheels 96 and 96' are at a fixed distance apart and can only be shifted together in axial direction.

The two movements of the iron required for the above ironing operation can naturally also be attained in another manner. As shown in Fig. 10 for example, the iron is supported on bars 119 which have rollers 9 at their upper ends. From the slot 11 of the stationary guide piece 10, two curved slots 11^a are branched off. On each end of this curved slot swinging parts or tongues 115 and 116 which act as switches are arranged. These tongues are connected with arms 117 which are controlled by tension springs 118 so that the switches normally are in the positions which are marked in the full lines. Supposing that the iron has the terminal left hand position and is moving in the slot 11 to the right hand, then before the iron reaches the right hand terminal position the switches 116 are turned by the rolls 9 into the dotted position, but as soon as the rolls release the switches the latter fall under the influence of the springs 118 back into their normal position. When afterward the iron moves to the left hand the rolls are guided by the switches 116 into the slots 11^a and the iron raised. When they arrive at the left hand end of the slots 11^a the rollers press the switches 115 into the dotted position from which they are returned into their normal position under the influence of the spring 118, as soon as they are released from the rolls 9. The iron has now been lowered again and the passage for the movement of the iron to the right hand side in the slot 11 is then clear again. The eccentric 37 imparts both movements to the iron in this arrangement. In this case only two guiding rollers 9 would preferably be provided, because a curved slot would have to be specially provided for each roller. The cam disks 24, 25 together with the gearing appertaining thereto could be entirely omitted in this form of construction.

The upward and downward movement of the iron at the ends of its stroke can also be obtained by having the hangers of the guiding member 10 not, as shown in Fig. 1, formed as toggle-levers, but by having them rigidly connected with the member 10 and having their upper ends provided with rollers, as shown in Fig. 11. In this arrangement the iron 4 is carried by rollers 9 running in the slot 11 of the member 10 which is in turn carried by means of bars 124 having rolls 122 at their top ends, engaging in oblique slots 121 of the sliding part 120 which is guided in guides 125; the sliding part 120 being periodically reciprocated by 130

bar 124' which is connected to a cam-disk or eccentric. The bars 124 pass through guides 126 and prevent longitudinal shifting of the member 10. When the sliding part 120 is moved to the left hand in its guides 125, the member 10, together with the iron 4 is lifted by the action of the slots 121 upon the rollers 122. When the movement of the sliding part 120 is reversed, the iron is lowered. The operation of the rod 38 for moving the iron longitudinally must be such in relation to the operation of the bar 124 that in the one final longitudinal position of the iron, the upward movement ensues and in the other final longitudinal position the downward movement ensues.

In the device shown in Fig. 12 the iron 4 is stationary and the table 2 is reciprocated and also moved upward and downward. The means for effecting this are similar to those shown in Fig. 1, corresponding parts being indicated by the same reference numerals with the suffix "a" and its operation will be readily understood without further description.

In the device shown in Fig. 13, the iron 4 which is depending from the bell crank levers 17 is arranged to have the upward and downward movement while the table 2, which slides in the guide member 127, moves in the ironing plane. The forms of construction as first described are, however, preferable, because in their case the ironing table on which the article to be ironed is laid remains at rest.

What we claim is:—

1. In an ironing machine, the combination of an iron; an ironing table; power driven means for reciprocating one of said members; and power driven means for moving one of said members toward the other member; manually operable starting means for the first named power driven means, and automatic means arranged to stop said first named power driven means upon completion of a predetermined period of operation of said power driven means.

2. In an ironing machine, the combination of an iron; an ironing table; power driven means for reciprocating one of said members; and power driven means for moving one of the said members toward the other member; manually operable starting means for said power driven means, and an automatic stop for the power driven means arranged for effective operation upon completion of a predetermined period of operation of said power driven means.

3. In an ironing machine, the combination of an iron; an ironing table; power driven means for reciprocating one of said members; power driven means for moving one of said members toward the other member; controlling means, for both of said power driven means, dependent on each

other so that said power driven means may be simultaneously started at the will of the operator; and means to automatically stop said power driven means.

4. In an ironing machine, the combination of an iron; an ironing table; power driven means for reciprocating said iron in one direction; and power driven means for reciprocating said iron in a direction transverse to said direction; and controlling means manually operable to start said first named means and arranged to stop the same automatically.

5. In an ironing machine, the combination of an iron; an ironing table; power driven means for reciprocating said iron in one direction; and power driven means for reciprocating said iron in a direction transverse to said direction; and controlling means manually operable to start both said means and arranged to stop the same automatically.

6. In an ironing machine, the combination of an iron; an ironing table; power driven means for reciprocating said iron in one direction; power driven means for reciprocating said iron in a direction transverse to said direction; controlling means, for both of said power driven means, dependent on each other so that said power driven means may be started at the will of the operator, and means to automatically stop said power driven means.

7. In an ironing machine, the combination of an ironing table; an iron; means for reciprocating said iron in a substantially horizontal plane; means for moving up and down said iron; and a common drive for both of said means; and controlling means manually operable to start said first named means and arranged to stop the same automatically.

8. In an ironing machine, the combination of an ironing table; an iron; means for reciprocating said iron in a substantially horizontal plane; means for moving up and down said iron; a common drive for both of said means; and controlling means manually operable to start both said means simultaneously and arranged to stop the same simultaneously.

9. In an ironing machine, the combination of an ironing table; an iron; means for reciprocating said iron in a substantially horizontal plane; means for moving up and down said iron; and a common drive for both of said means; couplings for connecting and disconnecting said means to or from said common drive; and automatically working means for actuating said couplings separately as well as together.

10. In an ironing machine, the combination of an iron; power driven means for reciprocating said iron in one direction; power driven means for reciprocating said iron in

a direction transverse to said direction; each of said means being under the control of the operator; and a control device common to both of said means.

5 11. In an ironing machine, the combination of an iron; an ironing table; power driven means for reciprocating said iron in one direction; and power driven means for automatically moving said iron, at each

10 end of its reciprocating movements, in a direction transverse to said direction, and controlling means manually operable to start both said means and arranged to stop the same automatically.

15 12. In an ironing machine, the combination of an iron; an ironing table; power driven means for reciprocating said iron; power driven means for moving up and down said iron; and controlling means manually operable to start both said means and arranged to stop the same automatically after a predetermined number of reciprocations of said iron.

20 13. In an ironing machine, the combination of an iron; an ironing table; power driven means for reciprocating said iron in one direction; power driven means for reciprocating said iron in a direction transverse to said direction; and controlling means operable manually to start both said means simultaneously and arranged to stop the same simultaneously after a predetermined number of reciprocations of said iron.

25 14. In an ironing machine, the combination of an iron; an ironing table; power driven means for reciprocating one of said members; power driven means for moving one of said members toward the other member; and controlling means manually operable to start the first named means and arranged to stop the same automatically after a predetermined number of reciprocations of said reciprocating member.

30 15. In an ironing machine, the combination of an iron; an ironing table; power driven means for reciprocating one of said members; power driven means for moving one of said members toward the other member; and controlling means manually operable to start both said means and arranged to stop the same automatically after a predetermined number of reciprocations of said reciprocating member.

35 16. In an ironing machine, a machine frame; an ironing table; a guide piece suspended on said frame and capable of being moved up and down but not shiftable laterally; an iron supported by said guide piece and capable of being reciprocated therein in a substantially horizontal plane; and power driven means for moving up and down said guide piece and for reciprocating said iron.

40 17. In an ironing machine, a machine

frame; an ironing table; a guide piece suspended by the intermediary of toggle-levers on said frame and capable of being moved up and down but not shiftable laterally; an iron supported by said guide piece and capable of being reciprocated therein in a substantially horizontal plane; power driven means for forcing sidewise and straightening out of the toggle-levers; and power driven means for reciprocating said iron. 70 75

18. In an ironing machine, a machine frame; an ironing table; a guide piece suspended by the intermediary of toggle-levers on said frame and capable of being moved up and down but not shiftable laterally; an iron supported by said guide piece and capable of being reciprocated therein in a substantially horizontal plane; means for forcing sidewise and straightening out of the toggle-levers; means for reciprocating said iron; and a driving shaft for both of said means; said first named means consisting of a bar engaging the middle joints of said toggle-levers and being connected to a rocking lever coöperating with a cam disk of said driving shaft. 80 85 90

19. In an ironing machine, a machine frame; an ironing table; a guide piece suspended by the intermediary of toggle-levers on said frame and capable of being moved up and down but not shiftable laterally; an iron supported by said guide piece and capable of being reciprocated therein in a substantially horizontal plane; means for forcing sidewise and straightening out of the toggle-levers; means for reciprocating said iron; and a common driving shaft for both of said means; said first named means consisting of a bar engaging the middle joints of said toggle-levers and being connected to a rocking lever coöperating with a cam disk of said driving shaft; said second named means consisting of an eccentric mounted on said driving shaft and being connected to said iron. 95 100 105 110

20. In an ironing machine, a machine frame; an ironing table; a guide in said machine frame substantially perpendicular to said ironing table; a guide-piece movable along said guide; a guide-way in said guide-piece substantially parallel to said ironing table; an iron supported by said guide-piece and capable of being reciprocated in said guide-way; and means for reciprocating said guide-piece along the guide of the machine frame and the iron along the guide-way of said guide-piece. 115 120

21. In an ironing machine, a machine frame; a substantially horizontal ironing table; a substantially vertical guide in said machine frame; a guide-piece movable along said guide; means to move said guide-piece up and down along said guide; a guide-way in said guide-piece substantially parallel to said ironing table; an iron guided in and 125 130

means to reciprocate said iron along said guide-way.

22. In an ironing machine, a machine frame; a substantially horizontal ironing table; a substantially vertical guide in said machine frame; a guide-piece movable along said guide and suspended on said machine frame; means to move said guide-piece up and down along said guide; a guide-way in said guide-piece substantially parallel to said ironing table; an iron guided in and means

to reciprocate said iron along said guide-way.

In testimony whereof we have signed our names to this specification in the presence of 15 two subscribing witnesses.

ARTHUR HAMMER.
FRITZ EGERSDÖRFER.
